UNITED STATES PATENT OFFICE

2,437,260

AUTOMOBILE CONTROL MECHANISM

Sergius T. Kobernick, Upper Darby, Pa.

Application November 8, 1945, Serial No. 627,382

5 Claims. (Cl. 192—3)

1

This invention relates to a super safety brake for motor vehicles, one of the objects being to provide an assembly of parts whereby, by exerting pressures in different directions with the foot of the user, the gas can be controlled, the starter circuit closed or opened and the brake applied or released.

Another object is to provide a structure which insures added safety through the fact that both the brake and gas always are under absolute integrated and coordinated control, and by which the time required for application of the brake has been reduced to an irreducible minimum insofar as is concerned the time required between a decision and a movement imposed by the foot of the operator.

A further object is to provide a structure whereby the foot of the driver is always in contact with the brake pedal and at the same time is yieldingly supported on a gas control lever which, in turn, is utilized as a starter circuit closer, so that the foot of the operator may remain in position at all times for closing the starter circuit, operating the gas-control lever during operation of the vehicle, and applying the brake.

A further object is to provide a structure of this character which normally constitutes a comfortable rest for the foot of the driver.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawing the preferred form of the invention has been shown.

In said drawing

Figure 1 is a view partly in side elevation and partly in section of the structure constituting the present invention, the normal position of the foot of the driver being indicated by broken lines.

Figure 2 is an elevation of the structure as viewed from the right in Fig. 1, a portion of the foot plate being broken away.

Figure 3 is a view on a reduced scale showing the connection between the structure and the carburetor.

Referring to the figures by characters of reference, 1 designates a bracket fixedly mounted on the floorboard 2 and pivotally connected to this bracket is a lever 3 the forward end 4 of which is connected by rod 5 to the carburetor so

2

that when said end is moved downwardly the flow of gas is cut down whereas when said end is moved upwardly the flow of gas is increased.

The other or rear end of the lever is provided with ears 6 constituting bearings for rollers 7 which, as shown, preferably converge backwardly so as to form a substantially V-shaped seat adapted to receive the heel portion of the shoe S of the driver.

10 This rear end of the lever carries a lug 8 positioned where it can move downwardly against and actuate the button 9 of a starter switch 10. A spring 11 is connected to the forwardly extended portion of lever 3 and is of such strength 15 as to support the back end of the lever in an intermediate position when subjected to the normal weight of the foot of the driver. This normal or intermediate position has been indicated in Fig. 1. It is to be understood that the spring 11 can 20 be adjustably connected at one end so as to adapt the lever for supporting feet of different weights.

The usual brake lever has been indicated at 12 and extends over lever 3. It is equipped with a foot plate 13 proportioned to provide a comfortable rest for the bottom of the foot of the operator. The lower portion of this foot plate can be forked as at 14 to straddle lever 3. In its normal position the foot plate is located where it can be engaged by the sole of the shoe of the 30 driver while the back of the heel of the shoe is resting comfortably on the rollers 7. Obviously with the parts positioned as in Fig. 1 the brake is off, and a normal supply of gas can flow to the engine.

35 When it is desired to use the structure for the purpose of starting the motor the driver may as desired press the toe portion of the foot forwardly to apply the brake and during this action the driver also presses downwardly with the foot in 40 a plane substantially parallel to the foot plate 13, so as to close the starter switch and increase the supply of gas to the motor. Thus the motor will be started as a result of this one operation. Thereafter by relieving pressure on the pedal 45 so that the foot rests only lightly thereon, and permitting the foot and leg to relax, the spring 11 which has been adjusted to the normal weight of the foot and leg will act to shift lever 3 and cause it to yieldingly support the foot in the 50 position shown at which time the flow of gas to the motor will be cut down to normal. With the foot and leg in relaxed position it is a simple matter to press the foot forwardly to apply the brake. Whenever desired a down pressure can 55 be exerted sufficient to partly or entirely over-

come the resistance of spring 11 for the purpose of increasing the flow of gas to the motor.

Importance is attached to the fact that by using the structure described the foot is always in position to instantly apply the brake and is in position at all times to accelerate the motor by increasing the gas simply by exerting a slight downward pressure against the rollers 1.

When the brake is fully applied to stop the vehicle, the foot of the operator, in moving the foot plate 13 forwardly, instantly and automatically leaves the lever 3, and the gas supply, by the very action of applying the brake as stated, is automatically cut off.

While these improvements are designed primarily for use on motor vehicles it is to be understood that they can also be associated with stationary motors of the internal combustion type.

What is claimed is:

1. The combination of a starter switch, of a spring restrained lever positioned to actuate the switch when said lever is moved at one end from normal position, means for connecting one end of the lever to a carburetor, a brake lever having a foot plate overlying the spring restrained lever, and a foot rest and support carried by the spring restrained lever.

2. A structure of the class described including a brake lever having a foot plate, a lever fulcrumed beneath the brake lever, a foot rest and support carried by one end of the lever and spaced from the foot plate, means for connecting the other end of said pivoted lever to a carburetor and adjustable resilient means for holding said pivoted lever normally in an intermediate position while being subjected to the weight of the foot mounted thereon.

3. A structure of the class described including a brake lever having a foot plate, a lever fulcrumed beneath the brake lever, a foot rest and support carried by one end of the lever and spaced from the foot plate, means for connecting the other end of said pivoted lever to a carburetor, and adjustable resilient means for holding said pivoted lever normally in an intermediate position while being subjected to the normal weight of the supported foot of the operator,

a starter switch in the path of the lever, and means carried by said lever for actuating said switch when the lever is moved to one extreme position under the action of the supported foot.

4. A structure of the class described including a brake lever having a foot plate for engagement by the sole of the shoe of an operator, and means extending under the foot plate for engaging and supporting the heel of said shoe, said means including a lever fulcrumed between its end, heel engaging means at one end of the lever, adjustable resilient means connected to the lever for resisting movement thereof under the normal weight of the supported foot of the operator, said lever being extended beneath the brake lever and foot plate, and means for connecting the lever to a carburetor.

5. A structure of the class described including a brake lever having a foot plate for engagement by the sole of the shoe of an operator, and means extending under the foot plate for engaging and supporting the heel of said shoe, said means including a lever fulcrumed between its ends, heel engaging means at one end of the lever, adjustable resilient means connected to the lever for resisting movement thereof under the normal weight of the supported foot of the operator, said lever being extended beneath the brake lever and foot plate, means for connecting the lever to a carburetor, a starter switch in the path of the lever, and means carried by the lever for actuating the switch when the lever is subjected to abnormal pressure by the supported foot.
